UNITED STATES PATENT OFFICE.

GEORGE E. PRENTICE, OF NEW BRITAIN, CONNECTICUT, ASSIGNOR TO TREO COMPANY, INC., A CORPORATION OF NEW YORK.

BUCKLE.

Application filed March 10, 1923. Serial No. 624,130.

To all whom it may concern:

Be it known that I, GEORGE E. PRENTICE, a citizen of the United States, residing at New Britain, in the county of Hartford and 5 State of Connecticut, have invented certain new and useful Improvements in Buckles, of which the following is a full, clear, and exact description.

This invention relates to a buckle for ad- 10 justably connecting together two bands, or a band to a garment, and particularly to a buckle having a sliding bar in a frame with the free end of the adjustable band passed through the frame at the further 15 side of the bar then over the bar, and then through the frame at the nearer side of the bar, so that any pull on the adjustable band will shift the bar automatically in a direction to clamp the free end of the band 20 between it and the frame. In prior buckles of this type, if the bars were narrow, considerable trouble was experienced because of their tendency to assume a diagonal position and bind in the guideways or fall out 25 when adjustments were being made, and if they were made wide enough to avoid binding in the grooves or falling out it was necessary to materially lengthen the frame, in order to provide space for sufficient travel 30 of the bar therein. An object of the invention is to provide an improved buckle of this type with which the binding or falling out of the sliding bar is avoided, without materially increasing the length of 35 the frame, if at all; which can be made entirely from sheet metal by simple stamping and bending operations; and which is attractive in appearance; light in weight, strong and durable in construction and in- 40 expensive. Other objects and advantages will be apparent from the following description of an embodiment of the invention, and the novel features will be particularly pointed out hereafter in claim.

45 In the drawing:

Fig. 1 is an elevation of an adjustable garter strap which has included therein a buckle constructed in accordance with the invention.

50 Fig. 2 is a longitudinal section through a portion of the same,

Fig. 3 is a transverse section through the buckle, and

Fig. 4 is a perspective of the two parts of a buckle separated from one another. 55

In the illustrated embodiment of the invention, a buckle frame 1 with a large aperture 2 therein, is stamped from sheet metal, and the two opposite side edge portions 3 and 4 thereof are doubled back upon the 60 stamping or blank toward one another on the same face of the blank or stamping. The doubled back edges are spaced slightly from the face of the blank which the edges overlie, so as to form with the blank two 65 opposing guide grooves which extend along the sides of the frame. An I-shaped stamping 5 of sheet metal is slidably disposed in the buckle frame, which is formed from the blank with the doubled back edges, so 70 as to bridge the aperture 2 from side to side between the guide grooves with the heads of the I-stamping sliding in the guide grooves. A strap 6 is looped through the aperture 2 at one end of the buckle 75 frame and stitched upon itself as at 7, so as to form a permanent connection between the buckle frame and the support. The adjustable strap or band 8 which, by way of illustration, may carry a 80 suitable garter fastener 9 at one end thereof, is passed through the aperture in the frame at the further side of the sliding bar (which is the side toward the strap 6), then passed around the sliding bar and back 85 through the aperture 2 in the buckle frame upon the nearer side of the bar.

When a pull is exerted upon the strap 8 it will be transmitted to the sliding bar in such a manner as to pull the bar in the 90 direction of pull upon the strap 8 and clamp the free end of the strap 8 between the sliding bar and the buckle frame. If one desires to lengthen or shorten the strap 8 it is merely necessary first to slacken it so 95 that the sliding bar may be shifted to release the free end thereof, after which the strap may be adjusted to the desired length. Thereafter when a pull is exerted upon the strap 8 it will shift the sliding bar in a direction to clamp the free end of the strap 100 in the buckle.

The sliding bar is preferably provided upon one face with a rib 10 which may be formed by pressing the same from the body of the sliding bar during the stamping operation, or by a subsequent operation in die machines. When the bar 5 is within the buckle frame the rib will extend into the aperture 2 and by engagement with the ends of the aperture limit the sliding movement of the bar. The bar 5 will be inserted under the cross bar before the flanged edges 3 and 4 are bent entirely down. After the bar is inserted, the edges may be bent entirely down so as to confine the bar within the grooves, and the rib 10 will prevent the bar from sliding entirely out of the buckle frame. The ends 11 of the flanges forming the guide grooves may be pinched downwardly towards the body of the buckle frame, as shown in Fig. 4, so as to form limit stops for the sliding bar 5.

It will be observed that the buckle frame and sliding bar may both be entirely produced by metal die stamping and bending operations, which enables their production in quantities at an extremely low cost. Their assembly is simple, and because of the large surface provided by the heads of the I-shaped sliding bar, the possibility of the bar binding in the grooves or assuming a diagonal position is avoided. At the same time the narrow intermediate part of the I-shaped stamping covers such a small portion of the aperture 2 that there will be a sufficient portion of the aperture which is not covered by the bar to enable the insertion and adjustment of the strap 8 without difficulty. At the same time the buckle

frame may be very short so as to be inconspicuous and light in weight. All parts of the buckle, being of metal, will be durable, and may be plated or given any desired finish.

The distance between the inner walls of the heads of the I-shaped sliding bar is preferably less than the width of the aperture 2, so that the strap 8 will be engaged along its edges only by the ends of the sliding bar and will not rub against the in-turned flanges 3 and 4. In this manner fraying of the edges of the adjustable strap will be largely avoided.

It will be obvious that various changes in the details, shapes, and proportions of parts herein described and illustrated for the purpose of explaining the nature of the invention, may be made by those skilled in the art within the principle and scope of the invention as expressed in the appended claim.

I claim:

A buckle comprising an apertured blank of sheet metal with two opposite side edges doubled back toward one another on the same face of the blank to form with the face of the blank two opposing guide grooves, and an I-shaped stamping of sheet metal bridging the aperture between the guides with the ends of the I sliding in the guides, the ends of the doubled back edges being pinched toward the body of the blank to close the grooves and limit the sliding movement of the I stamping.

In witness whereof, I hereunto subscribe my signature.

GEORGE E. PRENTICE.
